E. E. MURPHY,
LIQUID DISPENSING APPARATUS,
APPLICATION FILED JULY 28, 1916.

1,394,758.

Patented Oct. 25, 1921.

UNITED STATES PATENT OFFICE.

EDWARD E. MURPHY, OF WINCHESTER, MASSACHUSETTS.

LIQUID-DISPENSING APPARATUS.

1,394,758.

Specification of Letters Patent.

Patented Oct. 25, 1921.

Application filed July 28, 1916. Serial No. 111,827.

To all whom it may concern:

Be it known that I, EDWARD E. MURPHY, a citizen of the United States, residing at Winchester, in the county of Middlesex and 5 State of Massachusetts, have invented new and useful Improvements in Liquid-Dispensing Apparatus, of which the following is a specification.

This invention relates to liquid-dispensing devices, and particularly to those operated by means of a fluid under pressure, such as air or carbonic acid gas. The invention is embodied in the improvements which I will now proceed to describe and claim.

15 Of the accompanying drawings:

Figure 1 is a front elevation, showing parts of a soda fountain, including adjustable means for determining the amount of liquid to be delivered at each operation.

20 Fig. 2 is a view, partly in elevation and partly broken out, showing on a larger scale and in detail the parts included in the structure shown by Fig. 1.

Fig. 3 is an elevation of parts shown in 25 Fig. 2, as viewed from the right of that figure.

Fig. 4 is an enlarged longitudinal vertical section through a device for controlling the 30 operation of the apparatus, said controlling device being shown in side elevation at the upper right-hand corner of Fig. 1, and partly shown in front elevation at the upper part of Fig. 3.

Fig. 5 shows in horizontal section a portion of the device shown by Fig. 4, including 35 parts of modified construction, this view being on a larger scale than Fig. 4.

The same reference characters indicate the same or similar parts in all the views.

40 21 represents a measuring chamber, to the lower end of which is secured a pipe 20, extending to a syrup container at a higher level, the arrangement being such that the syrup or flavoring, passing through the pipe, 45 enters the bottom wall of the chamber through an opening covered by a clack valve 22, which valve permits ingress of the liquid until the level thereof in the pipes 26 and 51, hereinafter described, reaches a suitable 50 height, the valve closing when equilibrium has been established. The chamber 21 is made in two parts, as shown by Fig. 2, so that the bottom wall may be detached from the vertical wall to permit insertion of a 55 trap member 30.

On the top of the chamber 21 is a vertical

externally screw-threaded member 23 integral with said chamber or rigidly affixed thereto. Mounted on the member 23 is a headed adjusting member 24 having a hollow shank portion provided with internal screw-threads arranged to coact with the screw-threads on the member 23, so that the member 24 may be raised or lowered as it is rotated. The shank of the member 24 is 60 provided with external collars arranged to receive between them a lug 25 and to carry the lug 25 upward or downward as the adjusting member so travels. The lug 25 is rigidly connected to a pipe 26, and when the member 24 moves vertically it carries the lug and pipe 26 with it. The pipe 26 is 65 made of material having a certain degree of flexibility—such material, for instance, as block tin—and is curved so as to permit 70 flexure at its upper end, which flexure will be slight, however, as the vertical movement of the pipe is not great. The pipe 26 extends into the measuring chamber 21 through a stuffing box including a gland 27 and packing 28, the chamber 21 having a tubular portion 21^a formed to receive the gland 27, and having screw-threads arranged to coact with screw-threads on the gland, whereby when the gland is screwed down the packing may 75 be compressed and a tight slide joint be secured.

The pipe 26 terminates in an outlet nozzle 26^a, as shown by Fig. 1. The lower end of the pipe 26, within the chamber 21, has 90 attached to it a trap member 30 the free end of which is provided with a flange 30^a extending laterally outward, the inlet opening in said free end being substantially circular. A ball member 31 is arranged to 95 cover the inlet opening of the member 30, the ball being confined against translatable movement, except in a vertical path, by guide members 32, 32 which coact with the pipe 26 in restricting the ball member to 100 such vertical path. The guide members 32, 32 rise from the flange 30^a, being secured thereto in any desired manner, their upper ends being bent as shown in Figs. 2 and 3, if preferred, to coöperate with the stop member 33 which is attached to the pipe 26, to limit the path of upward travel of the ball.

The operation of the invention is as follows. Syrup from the before-mentioned 110 container flows by gravity into the measuring chamber 21 through pipe 20, forcing up

the clack valve 22 by its passage; and after the chamber 21 has been filled sufficiently to float the ball valve 31 the syrup continues to rise therein and will pass into the pipe 26, the flow being continued until the chamber 21 is filled and the syrup has risen in the pipes 26 and 51 to substantially the level of the surface of the syrup in said container. The clack valve 22 will then close by reason 10 of its own weight and prevent backward return of the syrup, which might otherwise occur under some conditions, as, for instance, when the container is removed from its delivering position while there is yet liquid 15 within it, or when the liquid is being forced from the chamber 21 by the compressed fluid in the manner now to be described.

In priming the measuring device, due allowance will be made for the approximate 20 amount of syrup that has entered pipe 26, and the amount to be delivered will be determined by the adjustment of the trap 30. Rotating the member 24 will raise or lower the pipe 26 and the trap 30. The higher the 25 trap, the less the amount delivered. The chamber is so proportioned that the trap will never require lowering to such an extent as to interfere with the effective working of the clack valve 22. The chamber 21 as 30 shown in Fig. 2 is about the actual size used for syrup dispensing in soda fountains equipped with my invention. The trap 30 may be positioned when the apparatus is installed and will rarely require any readjustment, if ever, unless a different quality or 35 character of syrup is to be dispensed.

The compressed air or other medium will be delivered at a pressure preferably between one and four pounds to the square 40 inch. When the dispensing clerk has placed a receptacle beneath the nozzle 26^a, pressure on a suitable plunger (not shown) will permit the compressed aeriform fluid to flow into the chamber 21. The force of the compressed 45 medium will drive syrup out of the chamber 21, up the pipe 26 and out of the nozzle 26^a until a sufficient quantity of the syrup has been forced out of the chamber 21 to allow the ball 31 to seat on the trap. 50 As long as the pressure on the plunger is continued, the force of the compressed medium in the chamber 21 will bear upon the ball 31 and hold it on its seat on member 30, thus preventing return to the chamber 55 of syrup from pipe 26; but when the plunger is released the pressure will be shut off, and the compressed medium will escape from chamber 21 through suitable conduit means not shown. The pressure on the ball 31 being 60 thus released, the excess syrup remaining in pipe 26 will return to chamber 21, where it will be kept cooler than it would be if allowed to remain in the upper portion of the pipe. In the meantime the syrup will 65 begin to flow from the container to the cham-

ber to refill the latter, and as soon as the syrup in the chamber 21 is sufficient to raise the ball 31 the syrup may rise in the pipe 26 to approximately the level of the syrup in the container. The entire operation is 70 capable of speedy and continued repetition.

Having thus explained the nature of my said invention and described a way of constructing and using the same, although without attempting to set forth all the forms in 75 which it may be made or all the modes of its use, what I claim is:

1. In apparatus of the class described, a measuring chamber provided with an outlet arranged to be raised and lowered relatively 80 to said chamber, a valve arranged to seat on said outlet, said valve being movable from its seat by the rise of liquid in said chamber, and guiding means for insuring the return of said valve to its seat when the valve is 85 permitted to descend.

2. In liquid-dispensing apparatus, a liquid supply source, a measuring chamber, means arranged to permit entrance of liquid from said liquid supply source to said chamber 90 and to prevent backward return of the liquid, means for delivering a fluid under pressure to said measuring chamber to cause the discharge of liquid therefrom, and means for controlling the flow of said fluid to said 95 measuring chamber, said controlling means being constructed and arranged to permit said fluid to exhaust from said measuring chamber when the supply of fluid is shut off. 100

3. In liquid-dispensing apparatus, a liquid supply source, a measuring chamber, means arranged to permit entrance of liquid from said liquid supply source to said chamber and to prevent backward return of the liquid, means for delivering a fluid under pressure to said measuring chamber to cause the discharge of liquid therefrom, and means for limiting the amount of liquid discharged, 105 said limiting means including a valvular member connected to a discharge pipe and arranged to be adjusted vertically in said measuring chamber. 110

4. In liquid-dispensing apparatus, a liquid supply source, a measuring chamber, means 115 arranged to permit entrance of liquid from said liquid supply source to said chamber and to prevent backward return of the liquid, means for delivering a fluid under pressure to said measuring chamber to cause 120 the discharge of liquid therefrom, and means for limiting the amount of liquid discharged, said limiting means including a discharge pipe a portion of which is movable and has an extremity extending slidably into said 125 measuring chamber, and a valve member arranged to seat on the inlet of said discharge pipe but to be movable from its seat by liquid in said chamber.

5. In liquid-dispensing apparatus, a meas- 130

- uring chamber having a valved inlet and a valved outlet, means for automatically charging the measuring chamber and operating by gravitational action, and means for supplying fluid under pressure to effect delivery of the charge from the measuring chamber and maintain the inlet valve in closed position during the delivery.
6. In liquid-dispensing apparatus, a measuring chamber having a valved inlet and a valved outlet, means for automatically charging the measuring chamber and operating by gravitational action, means for supplying fluid under pressure to effect delivery of the charge from the measuring chamber and maintain the inlet valve in closed position during the delivery, and means for relieving the fluid pressure in the measuring chamber after delivery to admit of automatic opening of the inlet valve and the recharging of the measuring chamber.
7. In liquid-dispensing apparatus, a measuring chamber having a valved inlet and a valved outlet, means for automatically charging the measuring chamber and operating by gravitational action, means for supplying fluid under pressure to effect delivery of the charge from the measuring chamber and maintain the inlet valve in closed position during the delivery, and means for relieving the fluid pressure in the measuring chamber after delivery to admit of automatic opening of the inlet valve and the recharging of the measuring chamber, the fluid pressure supply and the fluid pressure relieving means being connected for simultaneous movement to bring one into action and cut the other out of action in alternation.
8. The combination of a syrup jar for soda fountains having a chamber therein for measuring a charge of syrup to be delivered therefrom, a delivery nozzle connected to said chamber, means for admitting pressure

to said chamber to effect the delivery of said charge, and means for preventing the passage of said pressure to the nozzle after the charge has been delivered therefrom.

9. The combination of a syrup jar for soda fountains having a chamber therein for measuring a charge of syrup to be delivered therefrom, a delivery nozzle connected to said chamber, means for admitting pressure to said chamber to effect the delivery of the charge therefrom, means for preventing the passage of said pressure to the nozzle after the charge has been delivered therefrom, and means for providing for the escape of said pressure to permit the chamber to be recharged.

10. The combination of a syrup jar for soda fountains having a chamber therein for measuring a charge of syrup to be delivered therefrom, a discharge pipe connected to said chamber, means for admitting pressure to the chamber to effect the delivery of the charge therefrom, and a valve for closing said discharge pipe to prevent the discharge of pressure therethrough from the chamber after the charge has been delivered.

11. The combination of a syrup jar for soda fountains having a chamber therein for measuring a charge of syrup to be delivered therefrom, a discharge pipe connected to said chamber, means for admitting pressure to said chamber to effect the delivery of the charge, a valve for closing said discharge pipe to prevent the discharge of pressure therethrough from the chamber after the charge has been delivered, and a valve in the pressure inlet means for permitting the escape of said pressure after the charge has been delivered.

In testimony whereof I have affixed my signature.

EDWARD E. MURPHY.
